INVENTOR:
Harry A. Douglas
BY L. H. Engg Atty

UNITED STATES PATENT OFFICE.

HARRY A. DOUGLAS, OF BRONSON, MICHIGAN.

ELECTRIC SWITCH.

Application filed November 17, 1927. Serial No. 233,873.

My invention relates to electric switches and resides in the provision of improved means for moving one of two complementary contacts into and out of engagement with 5 the other.

In carrying out my invention, the movable contact is spring pressed and controlling means are employed for limiting the effective spring pressure upon the movable contact to 10 one direction to engage the movable contact with the other and to the reverse direction to separate the movable contact from the other. The movable contact is desirably provided upon a carrier. This carrier is provided 15 with a fulcrum and the controlling means serves to limit the effective spring pressure to one side or the other of the fulcrum point according to the direction in which the carrier and the contact thereon are to be 20 turned.

The means for applying the spring pressure to the carrier is desirably in the form of a spring which is separately formed from the carrier, this spring being preferably 25 stationarily located while the fulcrum is shiftable from either side to the other of the spring. This fulcrum is, in the preferred embodiment of the invention, provided upon a switch handle that is reciprocable 30 to place the fulcrum point on one side or the other of the spring, though the invention is not to be limited to rectilineal movement of the handle. Two stationary contacts are desirably provided and two movable contacts 35 are also provided which are respectively complementary to the stationary contacts, the two movable contacts being preferably separately formed from the contact carrier and in electrical connection with each other whereby 40 they are included in the same circuit with the stationary contacts when the switch is closed.

The invention will be more fully explained by reference to the accompanying drawing in 45 which Fig. 1 is a longitudinal sectional view of the preferred embodiment of the invention, the switch handle and the fulcrum thereon being shown in elevation, the switch, as illustrated in this figure, being in circuit 50 closing position; Fig. 2 is a sectional view on line 2-2 of Fig. 1; Fig. 3 is a sectional view on line 3-3 of Fig. 1; Fig. 4 is a sectional view on line 4-4 of Fig. 1; Fig. 5 is a view of some of the parts illustrated in 55 Fig. 1 showing the switch in a circuit opening position, some of the parts which are

shown in section in Fig. 1 being illustrated in elevation in this Fig. 5; Fig. 6 is a sectional view on line 6-6 of Fig. 1; and Fig. 7 is a perspective view illustrating the contact carrier and the contacts thereon. 60

The switch illustrated is provided with an enclosing casing having a cylindrical cup-shaped portion 1 which has a hollow stem continuation 2, this stem being threaded to 65 receive clamping nuts 3 and 4 between which the support 5 for the switch may be clamped. An insulating disc 6 closes or covers the cup, this disc being held against the edge of the cup by means of clips 7, formed upon 70 the cup, these clips being received within notches formed in the edge of the disc and being turned over upon the disc at their outer ends. Said disc carries the stationary metallic contacts 8 and 9, these contacts being 75 preferably in the form of posts having flanges 10 and 11 which engage an inner face of the disc and flanges or heads 12 and 13 at the outer side of the disc and which are riveted into engagement with the metallic terminal clips 14 and 15 which are 80 tightly held against the outer face of the disc. Binding screws 16 and 17 serve to clamp the circuit wires 18 and 19 into mechanical and electrical engagement with the 85 clips 14 and 15.

The movable contacts that are complementary to the stationary contacts are provided upon and are integrally formed with the V-shaped metallic plate 20, the end portions of this plate being respectively engageable with said posts. The plate 20 is formed with clips 21 that are received within notches formed within the insulating block 22 which is clinched by these clips 90 against this plate 20. The block 22 constitutes a part of the carrier for the movable contacts, the balance of the carrier being inclusive of a metallic plate 23 which is provided with clips 24 that are received within 100 notches formed in the block 22 and are clinched into engagement therewith, these clips being received in the space between the plate 20 and block 22 and being clear of this plate, this plate 20 being thus preferably free 105 of electrical connection with the plate 23. The latter plate is formed with a recess or socket 25 in the part of the plate which is continued upon one side of the block 22, this recess or socket receiving the outer end of 110 a plunger 26, the inner end of this plunger being received within a spring barrel 27.

assembled with the cup 1. This spring barrel is disposed upon a radius of the cup-shaped portion 1 as is also the spring 28 contained in the spring barrel. This spring 5 maintains the outer end of the plunger 26 in the socket 25. The carrier plate 23 is positioned, at one end, by a fin or rib 29 which is mounted upon the insulating disc 6 and enters the recesses 30 and 31 that are 10 respectively formed in one end of the plate 23 and the adjacent side of the insulating block 22. These recesses and the aforesaid fin also extend radially with reference to the cup 1 and take part in guiding the movement 15 of the carrier 22, 23 upon a radius of the cup as also does the radially sprung pressed plunger 26. The plate 23 is provided with ears 32 which embrace the spring barrel 27 whereby the radial movement of the plate 20 is guided.

The contact carrier comprising the block 22 and plate 23 thus floats, the circuit opening or closing position of the carrier being 25 positively defined by the fulcrum 33 which is preferably in the form of a flange upon a switch handle 34 that is desirably slidable within the bore of the cup stem 2, said handle having a gripping knob 35. When this handle is in its outermost position, the fulcrum 33 engages the adjacent end of the plate 23 so that the spring 28 is then effective to move the contact plate 20 against the contact terminals 8 and 9, as illustrated in Figs. 1 and 2. As illustrated in these 30 figures, the effective pressure of the spring is limited to a location between the fulcrum 33 and the contact plate 20. When the handle 34 is moved to its innermost position, the fulcrum 33 is placed in its alternative 35 position, Fig. 5, the fulcrum then being between the spring and the contact plate 20, whereby the contact plate 20 is withdrawn from the contacts 8 and 9, the effective pressure of the spring being now 40 upon the other side of the fulcrum point. It will be observed that the direction of the spring pressure in either position of the fulcrum is substantially parallel with the direction of movement of the contact plate 45 50 20 and its carrier. The portion of the plate 23 between the alternative positions of the fulcrum 33 is desirably bent to form a hump

23' in the path of movement of the fulcrum whereby the fulcrum is held in either of its alternative positions, the outward movement 55 of the handle 34 and the fulcrum 33 being also limited by engagement of said fulcrum with the inner end of the cup stem 2.

Changes may be made without departing 60 from the invention.

Having thus described my invention, I claim:

1. In an electric switch, the combination with a contact; of a carrier having a contact thereon that is complementary to the aforesaid contact; a fulcrum upon which said carrier may be turned, said carrier being spring pressed to effect turning movement thereof; and means whereby said fulcrum may be shifted to bring the effective spring pressure upon one side of the other of the fulcrum point to open or close the switch. 65

2. In an electric switch, the combination with a contact; of a carrier having a contact thereon that is complementary to the aforesaid contact; a fulcrum upon which said carrier may be turned, said carrier being spring pressed to effect turning movement thereof; and a reciprocable handle coupled with the fulcrum and serving to shift the fulcrum point to one side or the other of the place of effective spring pressure to open or close 70 the switch. 75

3. The structure of claim 1 wherein the carrier is provided with a hump which is interposed between the alternative positions of the fulcrum to take part in holding the fulcrum in such positions. 85

4. The structure of claim 1 wherein a spring separately formed from the carrier 90 presses upon the carrier in the direction of movement of the movable contact.

5. The structure of claim 2 wherein the carrier is provided with a hump which is interposed between the alternative positions 95 of the fulcrum to take part in holding the fulcrum in such positions.

6. The structure of claim 2 wherein a spring separately formed from the carrier presses upon the carrier in the direction of 100 movement of the movable contact.

In witness whereof, I hereunto subscribe my name.

HARRY A. DOUGLAS.
